[57] ABSTRACT

A supersonic shockwave tuyere for injecting a mixture of fuel into a shaft furnace. The tuyere has a convergent and a divergent portion and a sonic throat at the junction of the two portions. The convergent portion, the sonic throat and the first part of the divergent portion are formed in a first member which is releasably connected to a second member which forms a second part of the divergent portion, whereby upon change in the rate of the supply medium for support of the combustion, the first part may be exchanged against another part to modify the sonic throat as a function of such change.

SUPersonic SHOCK WAVE TUYERE

BACKGROUND OF THE INVENTION

The present invention relates to a shock wave tuyere of the type used in shaft furnaces to effect mixing of a fuel and a combustion-support medium, and the combustion of this mixture.

It has been proposed that part of the solid fuel used in shaft furnaces, in particular blast furnaces, be replaced by an auxiliary hydrocarbon fuel, for instance in liquid form, this fuel being injected into blast pipes opening into the shaft furnaces. Since the cost of solid fuel, in general coke, is relatively high, the effect of injecting an auxiliary fuel on the cost price of the product prepared in the shaft furnace depends on the rate of injection of auxiliary fuel. Attempts have therefore been made to reach injection rates as high as possible, while remaining compatible with satisfactory operation of the shaft furnace, especially from the aspect of the outflow of the charges treated in the said furnace. However, experience has shown that the auxiliary fuel injected burns increasingly incompletely as the injection rate rises, this incomplete combustion being accompanied by the formation of soot. This phenomenon necessitates keeping the auxiliary fuel injection rate at relatively low values.

The injection rate of a fuel may be substantially raised by increasing the degree of dispersion of the fuel in the gaseous combustion-supporting medium, and this enables the combustion conditions to be improved. One technique perfected by the applicants for this purpose consists in creating, in a tuyere of the Laval type for introducing fuel into a shaft furnace, a supersonic outflow in conditions such that the transition from the supersonic discharge rate to the subsonic discharge rate takes place in the divergent portion of the tuyere, that is to say that a shock wave is formed in said divergent portion, and in injecting a fuel into said tuyere upstream of said shock wave. Tests carried out with tuyeres of this type have shown the effectiveness of the action of dispersing the fuel in the combustion-support medium as it passes into the shock wave zone, this technique consequently permitting high fuel injection rates to be used without forming soot.

For a given pressure of the combustion-support medium at the inlet end of a tuyere of the type aforesaid it is known to calculate the geometrical characteristics of the tuyere to achieve the formation of the shock wave in the divergent portion of the tuyere. There are limits within which this pressure may vary, while maintaining the shock wave in the divergent portion of the tuyere and downstream of the fuel injection zone. Too large a pressure drop may however involve non-compliance with these conditions, and too large a pressure rise may lead to generating a supersonic outflow rate at the outlet from the divergent length of the tuyere. The extent of these limits between which the pressure may vary depends on the value of the pressure at the tuyere inlet, but is relatively restricted for the values envisaged in the context of introducing a combustion-support medium into a shaft furnace, for example hot air into a blast furnace. This is not in fact a serious disadvantage, since blast furnaces are increasingly designed to operate about a relatively constant reference pressure, corresponding to the air flow for the maximum production considered. It is thus permissible to design tuyeres in such manner as to allow the maximum

injection rate of auxiliary fuel commensurate with a tuyere geometry adapted to the reference pressure.

However, it may be found necessary to operate the shaft furnace at a rate other than that corresponding to the maximum production. In order to retain the advantages of auxiliary fuel injection during the corresponding periods, one must either replace all the injection tuyeres by a set of tuyeres of a geometry adapted in shape and size to the new operating rate, this constituting an extremely tedious operation which must in practice be excluded, or universal tuyeres must be designed with variable geometry, of relatively complex construction and doubtful reliability.

SUMMARY OF THE INVENTION

The object of the invention is to obviate or mitigate the aforesaid disadvantages, and more particularly to permit adaptations of the geometry of a tuyere for injecting an auxiliary fuel into a shaft furnace as a function of changes in the operating rate of said furnace, in order to permit maintenance of a maximum auxiliary fuel injection rate independently of changes in the rate of operation.

To this end, the subject of the invention is a supersonic shock wave tuyere for injecting a mixture of fuel and combustion-support medium into a shaft furnace. The tuyere has a convergent portion and a divergent portion with a sonic throat formed at the junction of the portion, said tuyere comprising a first member forming the convergent portion, the sonic throat and a first part of the divergent portion, a second fixed member forming a second part of the divergent portion, and means for removably connecting the first to the second member so that the first and second parts of the divergent portion are joined to form extensions of each other, whereby, upon change in the rate of supply of medium for support of combustion, the first member may be exchanged against another member to modify the sonic throat as a function of such change.

According to a preferred feature, the first member is equipped with means for injecting fuel into the tuyere, said tuyere being connected to a source of gaseous combustion-support medium.

According to a further feature, the source of combustion-support medium is constituted by the circulation of hot blast from a blast furnace.

According to a further feature, the divergent portion and the convergent portion are constituted by co-axial surfaces of revolution, the first and the second part of the divergent portions have the same cone angle and the sonic throat is constituted by the intersection of the surfaces of revolutions constituting the convergent and divergent portions in a plane normal to the common axis of these surfaces.

By virtue of its construction by two independent members, the tuyere according to the invention enables its geometric features to be modified with a view to adapting said features to a change in the rate of supply to the tuyere of combustion-support medium, so as to maintain specific flow conditions in the tuyere.

It will be understood that a change in the operating rate of a shaft furnace fitted with shock wave tuyeres for injecting fuel into a flow of gaseous combustion-support medium conveyed at supersonic speed, which change is manifested as a change in the flow rate and pressure of the combustion-support medium at the inlet of the tuyere, will involve a change in the flow proper-

ties of the combustion-support medium in said tuyere. In order to maintain in the divergent portion of the tuyere a shock wave indispensable for satisfactory dispersion of the fuel, the sonic throat stage is correlative modified by replacing the interchangeable member, which forms a species of a head of the tuyere, by a similar member adapted to the new conditions prevailing at the head end of the tuyere, the similar member having a sonic throat of different working section determined as a function of the new conditions of pressure and flow rate. This replacement can be effected very rapidly without removing the part of the tuyere integrated with the shaft furnace, and affects a readily accessible part of the tuyere.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings.

BRIEF DESCRIPTION OF THE DRAWING

FIG. 1 of the accompanying drawing shows a longitudinal section through one embodiment of a tuyere according to the invention for supplying auxiliary fuel into a blast furnace;

FIG. 2 illustrates, in cross-section a detail of FIG. 1; and

FIGS. 3 and 4 illustrate, likewise in cross-section, differently dimensioned elements which may be placed in the embodiment of FIG. 1, instead of the corresponding element shown therein.

DESCRIPTION OF THE PREFERRED EMBODIMENTS

The drawing shows a blast-furnace tuyere 1 of the shock wave type, this tuyere being disposed as an extension of a pipe 2 connected to the blast pipe of a blast furnace. The internal surface of the tuyere 1 is symmetrical about the longitudinal axis of the tuyere and includes a convergent portion 3 and a divergent portion 4. Where the portions 3 and 4 come together, there is formed a constriction or throttling portion 5, hereinafter called the sonic throat. The tuyere is fixed to an annular, preferably water cooled support 6 integral with the blast-furnace wall, and issues into the interior of the furnace near the upper part of the hearth.

In accordance with the invention, the tuyere is constituted by the association of two mutually complementary parts assembled together so as to constitute the internal profile of the tuyere, namely a first interchangeable member 7 forming a tuyere head and including the convergent portion 3, the sonic throat 5 and a first part 4a of the divergent portion, and a second substantially fixed member 8 forming the tuyere nose and including a second part 4b of the divergent portion issuing directly into the blast furnace interior, the second member being fixedly connected to the support 6. The tuyere nose comprises a hollow copper body 9 joined by brazing to a support plate 10 having an external frustoconical bearing surface 11 cooperating with a corresponding internal bearing surface formed in the support 6. An internal jacket or casing 12 is arranged in the body 9 and is in communication via a conduit 13 passing through the support plate with a source of cool-

ing liquid; the jacket 12 is also in communication with the interior of the body 9 through apertures 14 arranged at the end of the jacket, draining off of the cooling liquid taking place through holes (not shown) provided in the support plate. The member 7 has an external centering bearing surface 15 and an abutment surface 16 which cooperate respectively with an internal bearing surface 17 of the support plate 10 and with the external surface of the support plate in such manner that the member 7 and the nose of the tuyere can be contiguously disposed, with the convergent part 4b of the nose forming an extension of the convergent part 4a of the member 7. The first and second member of the tuyere may be joined together by screws 18 located at 120° intervals. An annular groove 19 is provided in the abutment surface 16 of the member 7 so as to form a chamber communicating both with the exterior of the tuyere via conduits 20 for admission of auxiliary fuel and with the interior of the tuyere near to the sonic throat 5 through injection conduits 21 directed towards the axis of the sonic throat. A fluid-tight packing 22 is located in a groove 23 provided in the external surface of the support plate 10, this packing being compressed by an annular projection 24 when the member 7 is mounted on the support plate. The pipe 2 is applied against a shoulder 25 on the member 7 by a tightening device 26 which enables rapid disconnection of the pipe 2.

As far as the manner of operation of the shock wave type tuyeres is concerned, it should be borne in mind that the internal profile of the tuyere, and in particular the surface area of the sonic throat, is designed for given values of the feed pressure, also known as the generating pressure, and of the ejection pressure, so that the combustion-supporting medium getting into the tuyere, in this case the hot blast, reaches the supersonic speed range at the tuyere throat, and that the transition to the subsonic speed range takes place in the divergent portion with correlative formation of a shock wave in said divergent portion. An auxiliary fuel such as a liquid hydrocarbon is introduced under pressure into the chamber 19 and is injected into the tuyere via the conduits 21. The auxiliary fuel entrained by the current of combustion-support medium mixes intimately therewith on passage through the shock wave formation zone, the mixture spontaneously ignites downstream of said zone under the effect of the ambient temperature and combustion will take place without formation of soot even at relatively high auxiliary fuel injection rates as compared with the rates applied in the art taken into consideration of injecting auxiliary fuel into blast furnaces. The tuyere profile is so fashioned that the fluctuations in pressure may reach 20% of the feed pressure corresponding to the desired rate of operation without causing upsets in the normal operation of the tuyere.

When it proves to be desirable to establish a different operating rate in the blast furnace, for instance, because the production of pig iron should be altered, the blast rate may vary in such manner that the tuyere profile no longer permits supersonic flow to be induced in the tuyere. The rate of injection of auxiliary fuel which can then be contemplated without forming soot may then be reduced by more than half, which results in making pig iron at higher unit cost price. The tuyere according to the invention enables the tuyere geometry to be rapidly adjusted to the new operation conditions.

It is known that the mass flow rate of a supersonic tuyere is proportional to the pressure prevailing at the tuyere inlet and to the surface area of the sonic throat. The profile of the tuyere is determined by rules well known to those skilled in the art for given values of feed rate and pressure, so that supersonic flow may be established in the tuyere with transition to the subsonic speed range in the divergent portion. The flow characteristics in the tuyere may be maintained when the flow rate is established at a value different from the preceding value, provided that substantially the same pressure prevails at the tuyere inlet, a result which may be obtained by modifying the extent of the sonic throat surface area. In order to do this, the pipe 2 is first removed, the blast delivery appropriate to the tuyere contemplated having been temporarily interrupted, then the first tuyere member 7 is removed and is replaced by another first member 7' or 7'' so formed that the surface area of the sonic throat 5' or 5'' differs from the surface area of the sonic throat 5 of the member 7; the ratio of the surface areas being substantially proportional to the ratio of flow rates for a given blast temperature. There is one feature common to the different first members tuyere in that the sonic throat thereof is constituted by the section through a plane perpendicular to the tuyere axis of a frusto-conical surface of revolution which has the same cone angle as the second part 4b of the divergent portion where the first part 4a of the divergent portion comes together with the second part 4b of said divergent portion. This surface of revolution is represented in broken lines and is denoted by the reference S in the drawing. The term "frusto-conical surface" is to be construed as indicating surfaces derived from both rectilinear and curvilinear generating lines, this latter case corresponding to tuyeres the divergent portion of which is of flared tubular shape. Moreover, the divergent portion may have this shape only in its second part 4b. It should be understood that the axial length of the divergent part 4a of the tuyere may be reduced until the surface area of the sonic throat corresponds to the surface area delimited by the circumference where the first and the second part of the tuyere come together.

The tuyere in accordance with the invention constitutes an injection device for gases and in particular for reducing gas mixtures which may find application in any plant involving the introduction of such gas mixtures. The tuyere finds particular application in shaft furnaces with the object of effecting the supply of a fuel and the combustion of the fuel in optimum conditions, while enabling these conditions to be maintained for different rates of feed of the medium supplied to the tuyere to support combustion. The fuel used may be a gaseous or liquid hydrocarbon product and may be particles of solid fuel in suspension in either of these media, as well as carrying any material which it is desired to introduce into the shaft furnace in a form compatible with the functioning of the injection device. The formation of the tuyere in two parts, one of which includes the fuel injection device, also enables the properties of this injection device to be selected as a function of the nature of the fuel injected. The invention is particularly applicable for the injection of an auxiliary fuel such as fuel oil by the tuyeres of a blast furnace with a view to replacing part of the coke used by this auxiliary fuel.

It will be understood that each of the elements described above, or two or more together, may also find

a useful application in other types of tuyeres differing from the types described above.

While the invention has been illustrated and described as embodied in a tuyere for the injection of an auxiliary fuel, such as fuel oil, into a blast furnace, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be protected by Letters Patent is set forth in the appended

1. A supersonic shock wave tuyere for injecting a mixture of fuel and a combustion-supporting medium into a shaft furnace, said tuyere having an unobstructed passage including a convergent portion and a divergent portion with a sonic throat at the junction of said portions, said tuyere comprising a first member forming said convergent portion, said sonic throat and a first part of said divergent portion; a fixed, hollow internally cooled second member forming a second part of said divergent portion; and means for removably connecting said first member to said second member so that said first and second parts of said divergent portion are joined to form extensions of each other whereby upon change of the rate of the supply medium for support of combustion, said first member may be exchanged for a different first member having a different throat area and adapted to be placed against the original second member to modify the sonic throat as a function of said change.

2. A tuyere as defined in claim 1, and including means incorporated in said first member for injecting fuel into the tuyere, and means connected to said first member for passing a gaseous combustion-supporting medium into the tuyere.

3. A tuyere as defined in claim 2, wherein said combustion-supporting medium is taken from a supply circuit of hot blast to a blast furnace.

4. A tuyere as defined in claim 2, wherein said divergent and convergent portions are constituted by coaxial surfaces of revolution, wherein said first and said second part of said divergent portion have the same cone angle, and wherein said sonic throat is constituted by the intersection of said surfaces constituting said divergent and convergent portions in a plane normal to the common axis of said portions.

5. A tuyere as defined in claim 2, wherein said means for injecting fuel into said tuyere comprises an annular chamber formed in said first member, passage means for feeding fuel into said annular chamber, and a plurality of passages communicating at opposite ends with said annular chamber and with the interior of said first part of said divergent portion downstream of said sonic throat.

6. A tuyere as defined in claim 2, wherein said second member comprises a support plate provided with a central opening defined by a frustoconical surface and a hollow body coaxially joined to said support plate and

defining a frustoconical passage of the same cone angle as said opening in said support plate.

7. A tuyere as defined in claim 6, wherein said hollow body is formed from a material having high thermal conductivity, and including a jacket arranged in said hollow body spaced from the inner surface thereof, and means for circulating a cooling fluid through said jacket and through the space between the latter and the inner surface of said hollow body.

8. A tuyere as defined in claim 6, wherein said sup-

port plate has an external frustoconical bearing surface, and including an annular support member adapted to be mounted in an opening of the shaft furnace, said support member having an internal frustoconical surface tightly engaged by said external frustoconical surface of said support plate.

9. A tuyere as defined in claim 6, wherein said connecting means removably connect said first member to said support plate.
